United States Patent Office

Des. 234,171
Patented Jan. 28, 1975

234,171

SEAT

Stapleton Long, Morristown, Tenn., assignor to The Berkline Corporation, West Springfield, Mass.

Filed May 29, 1973, Ser. No. 365,027

Term of patent 7 years

Int. Cl. D6—01

U.S. Cl. D6—71

FIG. 1.

FIG. 2.

FIG. 3.

FIG. 4.

FIG. 5.

FIG. 6.

FIG. 1 is a view, in front elevation, of a chair showing a preferred form of my design;

FIG. 2 is a view, in side perspective, of the chair of FIG. 1;

FIG. 3 is a view, in front elevation, of a chair showing another form of my design;

FIG. 4 is a view, in side perspective, of the chair of FIG. 3;

FIG. 5 is a view, in front elevation, of a sofa showing still another form of my design; and

FIG. 6 is a view, in side perspective, of the sofa of FIG. 5.

The chair and sofa backs are plain and conventional throughout and the sides not shown are identical to those shown.

I claim:

The ornamental design for a seat, as shown and described.
